PORTABLE CAST REINFORCED CONCRETE
STEP

Henry Schiele, Oradell, N. J.

Application April 3, 1935, Serial No. 14,391

1 Claim. (Cl. 72—96)

This invention relates to improvements in cement slabs and monoliths, with special references to the steps used in stairway construction.

Such steps are commonly used in the construction of buildings, both for private and public purposes, in the approaches to their entrances, underground store rooms, as cellars, and various other purposes above or below the ground surface.

10 It is well known that wooden steps crack, shrink, and warp, are prone to decay, due to exposure to rain, snow, and other conditions of weather, require frequent painting and eventually renewal at the owner's expense.

15 Steps made of bricks, in the course of time settle, crevices occur, and the mortar becomes loosened affecting the appearance and permanency of the steps.

20 Cinder and small cement blocks are subject to similar defects requiring resetting or replacement.

25 Concrete steps, poured in a wooden mould or form, made specially for the occasion are ordinarily faced with a different composition than that of their main body.

Such facing is apt to crumble, rendering the steps unsightly, and if built between side walls, shrink and draw away, leaving disfiguring gaps.

Having these matters in mind, it is an object 30 of the present invention to provide a solid pre-cast step, in the form of an elongated rectangle, suited to rest on bearing walls or abutments, bridging the space therebetween.

35 A further feature is in the provision of unitary blocks, of any desired length, made of superior materials, carefully selected and effectively bonded by metal reinforcements, applied in a novel manner, rendering them substantially unbreakable for their purpose as steps.

40 Another purpose is in the production of steps cast as units in metal moulds, assuring a desirable smooth surface and positive uniformity in dimensions.

Still another aim is to provide means whereby 45 the steps may be securely anchored to their side supporting walls in a manner to prevent cracks, crevices and gaps at their ends.

These and other valuable features, which will appear as the description progresses, are accomplished by the novel construction, combination and arrangement of parts hereinafter described and illustrated in the accompanying drawings constituting a material part of this disclosure, and in which:—

55 Figure 1 is a perspective view of an embodi-

ment of the device showing a single row of unitary steps, including support wall and guard rails.

Figure 2 is a similar view showing wider steps, each composed of a plurality of units resting on bearing walls at their ends.

Figure 3 is another like view showing the steps as disposed between raised side walls to which the steps are bonded.

Figure 4 is a front elevational view of a step indicated in Figure 1 with overhanging beads 10 at the front and ends.

Figure 5 is a fragmentary perspective view of a cross section of a step showing the reinforcing rods and binding wires.

Figure 6 is a broken perspective view showing 15 the manner of connecting the uppermost step to a platform.

Figures 7, 8, and 9 are perspective views of steps having variant shapes.

Figures 10 and 11 are views illustrative of different forms of tie rods.

Referring in greater detail to the drawings, Figure 1 is indicative of a conventional construction of steps, five in number, leading from a level yard or street surface 15 to a platform 16 ordinarily one step below the threshold of the building to which the steps lead.

The first or lowermost step A may rest directly on a suitable solid foundation, while the succeeding steps rest at their ends on brick walls 17 of 30 adequate width, as from twelve to sixteen inches, built upon a foundation.

Each step consists of a solid elongated precast slab, of generally rectangular cross section, presenting at the front a riser 18 and tread 19 having a bead 20 at its front upper edge, which, as shown in Figure 1, may also extend at its ends.

The tread 19 is preferably roughened, as indicated, to prevent an effective non-slip surface, the end and rear margins being smooth.

The length of the steps may vary in dimensions from four to eight inches for the height of the riser, are ordinarily twelve inches for the width to seven feet in length; if longer steps are required two or more of the slabs are preferably 45 used with their ends abutting, as indicated in Figure 2.

Holes 21 may be formed in the steps to receive posts 22 surmounted by hand rails 23 and carry guard rails 24 if desired.

When two or more sections are required to complete the full length of the steps, support walls 17a, preferably of the same width as the outer walls 17 are desirable to use in order that the steps be adequately sustained.

If, as shown in Figure 3, an outer wall 17b is preferred, the ends of the steps are level and closely arranged against the inner surface of the wall.

5 The steps are cast in heavy metal moulds from a mixture of the following ingredients:—

	Parts
Portland cement, by measure.....	1
Clean, coarse sand.....	2
10 Crushed blue stone.....	4

The blue stone to be free of dust and of a size to pass through a screen of half inch mesh.

15 These ingredients to be intimately mixed and combined with water to form a free flowing mixture.

When approximately two inches of the mass has been poured into the mould which is maintained level, a skeleton frame F, (see Figs. 5 and 6) is entered and the pouring continued.

20 The frame consists of four steel rods 25—25', of any preferred cross section and substantially three eighths of an inch in cross section, twisted, corrugated or otherwise roughened to be firmly seized by the cementitious mixture in a semi-fluid or highly plastic consistency, the rods being so arranged as to be essentially equally spaced from the corners of the step to be cast, and of a lesser length, so that their ends are covered by the material.

25 A single central rod 26 is also cast into the step, constituting one of the elements of the frame.

30 These several rods are held in their respective positions, during insertion, pouring and embedding, by tie wires 28 arranged at spaced intervals as seen in Figures 1, 4, and 5.

If the ends of the steps abut a fixed upright wall, the center rod 26 is extended and bent at an angle forming anchors 27 to be inserted in 35 the wall, (see Fig. 3) or the extending ends may be downturned to engage the support walls on which they rest.

35 As seen in Figure 6 the top step E may be

bonded to the platform 16 by cross rods 30, anchored in the step by angularly turned ends 31 and in a similar manner to the platform.

Longitudinal rods 32, acting as additional reinforcements are bonded by wires 33 tying the 5 several rods together.

Steps H, I and J, other than rectangular profile, as shown in Figures 7, 8 and 9 are provided with internally embedded reenforcing rods 25'—26' may be made in a similar manner to 10 present a choice in the selection of appearance, their construction being essentially the same as previously described.

15 It will be apparent that precast steps made of the materials and in the manner specified, if 15 properly erected, will maintain their integrity indefinitely long, requiring no repairs, replacements or expense after installation.

20 From the foregoing it will be seen that a simple device for this purpose has been disclosed 20 in the preferred form of its embodiment, but it is not desired to restrict the details to the exact construction shown, it being obvious that changes may be made without departing from the scope 25 of the appended claim.

Having thus described the invention, what is claimed as new and desired to secure by Letters Patent, is:—

As a new article of manufacture, a solid slab 30 constituting a stair step of substantially uniform rectangular cross section throughout its entire length, straight corrugated longitudinal reenforcing rods cast into said slab adjacent its four lengthwise corners, a single straight reenforcing 35 rod passing lengthwise through the approximate center of said slab, said first named rods being completely embedded therewithin and said last named rod extended at both ends and bent at right angles to form anchors to engage end supports for the slab, and tie wires bonding all 40 of said rods at intervals along their length.

HENRY SCHIELE.
